United States Patent Office.

WILLIAM H. SHORT, OF BROOKLYN, NEW YORK.

Design No. 4,850, dated April 25. 1871.

DESIGN FOR A SASH-WEIGHT.

The Schedule referred to in these Letters Patent and making part of the same.

I, WILLIAM H. SHORT, of Brooklyn, in the county of Kings and State of New York, have invented and produced a new and original Design for Sash-Weight, of which the following is a specification.

The body is cylindrical. The upper end is wedge-formed, with the faces slightly hollowed, topped by a staple of a semi-ring form where it appears, the roots or legs of the staple entering the thick portions at the side of the top.

The top within the staple is hollowed.

The exact nature of the design is clearly and fully represented in the accompanying drawing, in which—

Figure 1 is a side elevation; Figure 2, another view, in section, at right angles to the first; and

Figure 3, a plan view.

I claim as my invention—

The design for a sash-weight, as shown and described.

WM. H. SHORT.
